LIQUID FUEL BURNER

Earl C. Vollmer, Rock Island, Ill., assignor to
Micro-Westco, Incorporated, Bettendorf, Iowa,
a corporation of Delaware

Application July 15, 1936, Serial No. 90,671

4 Claims. (CL 158—1)

The present invention relates to heating units and more especially heating units of the oil burning type for use in conjunction with hot air, hot water, or steam heating plants for the heating of houses, stores, and the like. It is found that in furnaces of a certain type, particularly those in which the overall efficiency is high, there is a certain variation in air pressure causing fluctuation of the burner flame and unpleasant pulsations, resulting in undue noise when the burner unit is operating. It is the main purpose of this invention to provide a structure and mode of operation which will obviate the difficulty referred to and which is experienced by most users of the type of furnace mentioned. Another object of this invention is the provision of an improved mode of draft control whereby the draft through the heating unit to the furnace may be regulated to a nicety and in accordance with the amount of oil consumed. Such further objects, advantages, and capabilities as will hereafter appear and as are inherent in the construction disclosed herein are also contemplated. My invention further resides in the combination, construction, and arrangement of parts illustrated in the accompanying drawings and, while I have shown therein what is now regarded as the preferred embodiment of this invention, I desire the same to be understood as illustrative only and not to be interpreted in a limiting sense.

In the drawings annexed hereto and forming a part hereof,

Fig. 1 represents a side elevation, partly broken away and in section, illustrating my present invention;

Fig. 2 represents an end elevation taken in the direction indicated by the arrows 2—2, Fig. 1;

Fig. 3 represents a fragmentary section approximately along the plane indicated by the line 3—3, Fig. 1.

Reference will now be made in greater detail to the annexed drawings for a more complete description of this invention. The casing of the burner is denoted, in general, by the numeral 1 while the end of the burner unit, which is inserted into the combustion chamber of the furnace, is indicated by the numeral 2. A flange 3, adjacent the part 2, provided with bolt holes 4, furnishes means for the attachment of this burner unit to the furnace wall. Since no novelty is claimed in this application in the electrodes, fuel delivery pipe, burner nozzle, etc., a description thereof will not be entered into further than to say that they are located in the

channel 5 through which passes the air delivered by the fan 6.

Of the pipes 7 and 8, one serves as a fuel inlet and the other as a by-pass back to the fuel tank from the pressure valve located in the casing 9. The pipe for carrying the fuel from the pressure valve to the tube, by means of which the fuel is carried to the nozzle, is indicated at 10. The fan 6 is located in the fan casing 11 and is driven by the motor indicated at 12. The inlet to the fan is indicated at 13 and through this inlet passes the shaft 14 which drives the oil pump in the casing 9.

The main air inlet pipe is indicated at 15 and this is controlled by a valve 16, adjustable to carry the amount of air passing into the fan in accordance with the amount of oil being fed through the tube 10 and the nozzle. An auxiliary air inlet 17 is controlled by a valve 18, adjustable as desired. An opening 19 leads out through the lower part of the unit 2 and is controllable, as desired, by the valve 20. The openings 17 and 19 unite in the opening 21, which opens sidewise, as indicated at 22, into the hollow of the projection 23 extending from the casing 24 which is secured to the side of the fan housing or casing 11. Therefore, it will be seen that auxiliary air entering the opening 17 and gases from the combustion chamber, passing through the opening 19, will co-mingle and pass through openings 21 and 22 to the inlet side of the fan 6.

When a large amount of oil is being consumed, the valve 16 should be open to supply as much air as is needed for the combustion of the fuel. At the same time that valve 20 is partially open, valve 18 is partially closed, this adjustment permitting relief of pressure in the combustion chamber. On the other hand, when the oil consumption is very small, valve 16 should be mostly closed and valve 18 fully opened to give the desired supply of air for the fuel consumed and reduce to a minimum the suction through the opening 19.

During the operation of the burner, there is a certain stage during which the inertia of the gases in the stack and the expansion of the burning fuel in the combustion chamber are likely to reduce to an undesirable extent the amount of air delivered by the fan, with the result that there is incomplete combustion, producing a hazardous condition in the furnace. By having the valve 20 open, this pressure in the combustion chamber may be relieved and the gases, passing out through the opening 19 past the valve 20, will be drawn into the fan and again

forced into the combustion chamber. These gases are co-mingled with cold air passing through the opening 17 and thus there is a tendency to keep the apparatus at a reasonable operating temperature. The provision of the opening 19 from the combustion chamber to the fan intake makes it possible to prevent the escape of furnace gases into the furnace room.

It will of course be understood that the specific description of structure set forth above may be departed from without departing from the spirit of this invention as set forth in this specification and the appended claims.

Having now described my invention, I claim:

1. An oil burning unit of the pressure atomizing type for use with a furnace having a combustion chamber, comprising a fan housing having a fan located therein and provided with a main air-inlet, a burner nozzle, an air conduit for conducting air from the fan housing to the combustion chamber and delivering it around said nozzle, an auxiliary air-inlet communicating with the main air-inlet, a second conduit communicating with said auxiliary air inlet and having its inlet 25 in the combustion chamber in the vicinity of the nozzle, regulating means for regulating the amount of free air admitted through the main air-inlet, regulating means for regulating the flow of air through the auxiliary air-inlet, and regulating means for regulating the flow of gases from the combustion chamber to the stream of air flowing through the auxiliary air-inlet.

2. In an oil-burning apparatus of the pressure

atomizing type for use with a furnace having a combustion chamber, having a nozzle, an air-carrying conduit for supplying air to support combustion, a fan for forcing air through the conduit and having a main air-intake, an auxiliary air-intake for said fan, and a passageway leading from the vicinity of the burner nozzle to said auxiliary air-intake, whereby products of combustion from the combustion chamber are mixed with the air flowing through said auxiliary air-intake.

3. In an oil-burning apparatus of the pressure atomizing type for use with a furnace having a combustion chamber, having an oil spray nozzle, an air conduit for supplying air to support combustion, a fan for forcing air through the conduit and having a main air-intake, an auxiliary air-intake for said fan, a passage-way leading from the vicinity of the spray nozzle to said auxiliary air-intake, whereby products of combustion from the combustion chamber are mixed with the air flowing through said auxiliary air-intake, a valve for regulating the amount of air admitted through the main air-intake, a valve for regulating the flow of air through the auxiliary air-intake, and a valve for regulating the flow of gases from the combustion chamber to the stream of air flowing through the auxiliary air-intake.

4. A structure as defined by claim 3 in which the auxiliary air-intake has a carrying capacity less than that of the main air-intake.

EARL C. VOLLMER.
